CLAIM

The ornamental design for a solar charger, as shown and described.

DESCRIPTION

FIG. 1 is a rear, top and left side perspective view of a solar charger, showing my new design;

FIG. 2 is a use state view thereof;

FIG. 3 is a front, bottom and right side perspective view thereof;

FIG. 4 is a front view thereof;

FIG. 5 is a rear view thereof;

FIG. 6 is a left side view thereof;

FIG. 7 is a right side view thereof;

FIG. 8 is a top plan view thereof;

FIG. 9 is a bottom plan view thereof;

FIG. 10 is a closed state view thereof; and,

FIG. 11 is another closed state view.

Dotted lines included in the drawings show portions of the solar charger that form no part of the claimed design. Longer-dash lines included in FIG. 2 illustrate unclaimed environmental structure, while the same longer-dash lines in FIG. 10 show unclaimed surface features of the solar charger.
